(57) **CLAIM**

The ornamental design for control arm for cement mixer, as shown and described.

DESCRIPTION

FIG. 1 is a perspective view from rear and right side of a control arm for a cement mixer embodying our new design, the cement mixer being shown in broken lines for illustrative purposes only.

FIG. 2 is a perspective view from front, left side and above of the control arm; and,

FIG. 3 is a rear view of the control arm.
